United States Patent Office.

J. W. BISHOP, OF NEW HAVEN, CONNECTICUT.

Letters Patent No. 89,970, dated May 11, 1869.

IMPROVED PICTURE-NAIL.

The Schedule referred to in these Letters Patent and making part of the same

To all whom it may concern:

Be it known that I, J. W. BISHOP, of New Haven, in the county of New Haven, and State of Connecticut, have invented a new Improvement in Picture-Nails; and I do hereby declare the following, when taken in connection with the accompanying drawings, and the letters of reference marked thereon, to be a full, clear, and exact description of the same, and which said drawings constitute part of this specification, and represent, in—

Figure 1, a view of the nail complete, and in
Figure 2, a central section enlarged.

This invention relates to an improvement in the article of manufacture commonly known as picture nails, which are used for various purposes, the object being to cap a common cut-nail so as to ornament the head, and give to it a finished appearance. To this end

The invention consists in placing a disk of sheet-metal over the head of a common cut-nail, and in a die prepared for the purpose, close the disk over so as to cover the head, and, at the same time, to swage the head into proper form.

In order to the clear understanding of my invention, I will fully describe the same as illustrated in the accompanying drawings.

A is a common cut-nail, its head, as usual, nearly square, but of no regular or defined shape.

Over such a head I place a disk, B, of sheet-metal, and then, in dies prepared for the purpose, strike the cap and head into shape, as seen in fig. 1 and in fig. 2, enlarged, where the original nail is shown in neutral tint, and its form, after the process of capping, denoted in red. This caps the nail, so that it may be driven in the usual manner of driving such nails, the head having an oval plated appearance, and this with very slight addition to the cost of the nail, much less than what is known as the "French nail," the nail which is commonly capped.

I do not wish to be understood as broadly claiming capping the heads of nails, as such, I am aware, is not new, the process of capping herein described fully illustrating the difference between the common process of capping and my own.

Having fully described my invention,

What I claim as new and useful, and desire to secure by Letters Patent, is—

A cut-nail, the head of which, without previous preparation, or change of form, is covered with a cap of metal, in the manner described and set forth, as an article of manufacture.

J. W. BISHOP.
